UNITED STATES PATENT OFFICE.

GILBERT S. ALLEN, OF EVERETT, MASSACHUSETTS.

CASTER.

1,160,121.

Specification of Letters Patent. Patented Nov. 16, 1915

Application filed March 22, 1915. Serial No. 15,996.

To all whom it may concern:

Be it known that I, GILBERT S. ALLEN, a citizen of the United States, and a resident of Everett, in the county of Middlesex and State of Massachusetts, have invented certain new and useful Improvements in Casters, of which the following is a specification.

This invention relates to casters for supporting relatively heavy loads, such as pianofortes.

The invention has for its object to provide an improved construction permitting the yoke or frame on which the caster wheels are mounted, to turn freely on a vertical axis, and permitting the wheel to be made in independently rotatable sections, each adapted to turn freely on a horizontal axis, anti-friction bearings being provided and the construction being such that the parts, including the anti-friction rollers of said bearings may be conveniently assembled.

The invention also has for its object to enable the wheel bearings to be conveniently lubricated and protected against the admission of dirt.

The invention consists in the improvements which I will now proceed to describe and claim.

Of the accompanying drawings forming a part of this specification: Figure 1 represents a side elevation of a caster embodying my invention; Fig. 2 represents a section on line 2—2 of Fig. 1, showing the wheel made in two independent sections; Fig. 3 represents a view similar to a portion of Fig. 2, showing the wheel sections and their bearings assembled prior to engagement with the load-engaging yoke or frame; Fig. 4 represents a view similar to a portion of Fig. 2, showing said yoke or frame; and Fig. 5 represents a view similar to Fig. 2, showing the wheel made as a single piece or part.

The same reference characters indicate the same or similar parts in all the views.

Referring first to Figs. 1, 2, 3 and 4, 12 represents a yoke composed of a neck portion 12^a and spaced-apart arms 12^b. The neck 12^a is provided with suitable load-engaging means whereby it may be connected with a load member, such as the leg of a pianoforte, said means as here shown including a vertical spindle 13, rigidly attached to the neck and projecting upwardly therefrom. The neck is preferably reinforced by a plate having an upwardly fac-

ing face 12^c surrounding the base of the spindle and an upwardly projecting marginal flange or dam 12^d surrounding said face and adapted to confine grease in the horizontal roller race of which the face 12^c forms a part.

14 represents a bushing adapted to be inserted in a socket in a piano leg and provided at its lower end with a horizontal flange 14^a, the under side of which forms a horizontal downwardly facing face opposed to the face 12^c. Between said faces or race members I interpose a circular series of anti-friction rollers 15, preferably balls, which are confined by an annular flange 14^c on the flange 14^a. The upper end portion of the spindle 13 is preferably provided with a circumferential groove 13^a between which and the inner surface of the bushing 14 is confined a horizontal series of anti-friction balls 16. Grease may be inserted in the roller race thus formed, and confined by the dam 12^d.

The yoke 12 is adapted by the described means to turn on a vertical axis with the minimum of friction. It will be understood, however, that I do not limit myself to the described means for connecting the yoke with the load, and may employ the construction next described in connection with any other suitable load-engaging means.

17 and 17^a represent headed screws inserted in orifices 18 (Fig. 4) formed in the lower end portions of the yoke-arms 12^b, said screws being insertible endwise in said orifices and their heads being adapted to bear on the outer sides of the yoke-arms. The said screws are engaged with threaded sockets formed for their reception in a cylindrical axle 19 inserted between the yoke-arms.

The axle 19 constitutes a fixed bearing which is surrounded by an annular caster wheel, which is preferably composed of two independently rotatable sections 20, each of which constitutes in effect a separate wheel. Each section 20 has an outer annular shoulder 21 and an inner annular shoulder 22, said shoulders being concentric with the periphery of the axle 19 and spaced therefrom, so that zones of said periphery are opposed to the said shoulders, the said shoulders and zones forming roller race members. Between the outer shoulders 21 and the axle 19 I interpose an outer series of anti-friction rollers 23, preferably balls, and between the

inner shoulders 22 and the axle 1 interpose an inner series of similar anti-friction rollers 23^a. Each wheel section 20 is provided with a spacing or separating member 24 projecting between the balls 23 and 23^a. The outer balls 23 are confined by outer confining plates 25, preferably of hardened steel, adjacent to the outer sides of the wheel sections 20, said plates being preferably 10 provided with flanges 26 projecting into annular grooves 27 formed in the outer sides of the wheel sections, the said plates and flanges being free from contact with the wheel sections and with the sides of said 15 grooves, and the plates being clamped by the screw heads against rotation between the yoke-arms and the ends of the axle 19.

28 represents an intermediate confining plate interposed between the wheel sections 20 and confining the inner balls 23^a in their races. The said intermediate confining plate is provided with two oppositely projecting flanges 29 projecting into annular grooves 30 formed in the inner sides of the wheel 25 sections 20. The flanges 29 are also in close proximity to the outer sides of the grooves 30, but not in contact therewith, the object of the flanges of both the outer and the inner confining plates being to prevent the admission 30 of dirt and grit to the ball races formed by the wheel shoulders, the axle and the confining plates.

The axle 19 is preferably hollow, its interior forming a grease chamber 31, which 35 communicates through grease outlets 31^a with the several ball races, as shown by Fig. 2. Said chamber is closed at one end by the screw 17, the screw 17^a being provided with a grease inlet 17^b having a removable closure 17^c. Provision is thus made for forcing grease into the roller races, and for retaining it therein.

The wheel sections, axle, confining plates, and rollers may be assembled as a unit in 45 the manner indicated by Fig. 4, before engagement with the yoke, the unit or assemblage of parts shown by Fig. 4 being inserted as one part between the yoke-arms and secured thereon by subsequently inserting 50 the screws 17 and 17^a.

The construction whereby the parts are enabled to be assembled as indicated permits the convenient location of the anti-friction rollers in their proper relative positions, and 55 prevents any liability of loss or displacement of the rollers during the assembling operation.

The caster may be provided with a wheel 20^a formed as a single piece or part, as 60 shown by Fig. 5, the intermediate confining plate 28 being omitted. Fig. 5 also shows as the means for engaging the axle with the yoke-arms a tubular stud or rivet 35, the ends of which are expanded against the 65 yoke-arms to form clamping shoulders 36.

Said stud may receive grease through one of its ends, and has a grease outlet 37 communicating with a grease chamber in the axle, here designated 19^a. The ends of the stud may be internally threaded to engage screw plugs 38, either of which may be removed to permit the introduction of grease. The spindle 13 may be frictionally retained in the bushing 14 by an expandible ring 39 engaged with a groove in the upper end 75 portion of the spindle and having a frictional bearing on the interior of the bushing. The bushing may in turn be frictionally engaged with a socket in a piano leg by a similar ring engaged with a groove 40 in the upper end portion of the bushing. 80

Having described my invention, I claim:

1. A caster comprising a load-engaging two-armed yoke, an axle interposed between the yoke arms, an annular wheel surrounding the axle and having inwardly facing annular bearing shoulders concentric with the periphery of the axle, and an inwardly projecting separating member between said shoulders, confining plates interposed between the yoke arms and the ends of the axle, and extending across said ball races, said shoulders, separating members, confining plates and axle forming annular races, anti-friction rollers confined in said races, and securing means engaging the axle with the yoke arms and clamping the confining plates between said arms and the ends of the axle. 90

2. A caster comprising a load-engaging two-armed yoke, an axle interposed between the yoke arms, an annular wheel surrounding the axle and having inwardly facing annular bearing shoulders concentric with the periphery of the axle, and an inwardly projecting separating member between said shoulders, confining plates interposed between the yoke arms and the ends of the axle, and extending across said ball races, said shoulders, separating members, confining plates and axle forming annular races, anti-friction rollers confined in said races, and securing means engaging the axle with the yoke arms and clamping the confining plates between said arms and the ends of the axle, the wheel being provided with annular grooves in its sides, and the confining plates being provided with annular dirt-excluding flanges projecting into said grooves. 110

3. A caster comprising a load-engaging two-armed yoke, an axle interposed between the yoke arms, an annular wheel surrounding the axle and having inwardly facing annular bearing shoulders concentric with the periphery of the axle, and an inwardly projecting separating member between said shoulders, confining plates interposed between the yoke arms and the ends of the axle, and extending across said ball races, said shoulders, separating members, 120

125

130

confining plates and axle forming annular races, anti-friction rollers confined in said races, and securing means engaging the axle with the yoke arms and clamping the confining plates between said arms and the ends of the axle, the axle and securing means being formed to conduct grease to the said races.

4. A caster comprising a load-engaging two-armed yoke, an axle interposed between the yoke arms, an annular wheel surrounding the axle and having inwardly facing annular bearing shoulders concentric with the periphery of the axle, and an inwardly projecting separating member between said shoulders, confining plates interposed between the yoke arms and the ends of the axle, and extending across said ball races, said shoulders, separating members, confining plates, and axle, forming annular races, anti-friction rollers confined in said races and headed screws engaging the yoke arms with the axle and clamping the confining plates between said arms and the axle.
5. A caster comprising a load-engaging two-armed yoke, an axle interposed between the yoke arms, an annular wheel surrounding the axle and having inwardly facing annular bearing shoulders concentric with the periphery of the axle, and an inwardly projecting separating member between said shoulders, confining plates interposed between the yoke arms and the ends of the axle, and extending across said ball races, said shoulders, separating members, confining plates and axle forming annular races, anti-friction rollers confined in said races, and securing means engaging the axle with the yoke arms and clamping the confining plates between said arms and the ends of the axle, said axle being provided with a grease chamber and with a grease outlet communicating with said races, and the securing means being adapted to conduct grease to said chamber.
6. A caster comprising a load-engaging two-armed yoke, an axle interposed between the yoke arms, an annular wheel surrounding the axle and having inwardly facing annular bearing shoulders concentric with the periphery of the axle, and an inwardly projecting separating member between said shoulders, confining plates interposed between the yoke arms and the ends of the axle, and extending across said ball races, said shoulders, separating members, confining plates and axle forming annular races, anti-friction rollers confined in said races, and headed screws engaging the yoke arms

with the axle and clamping the confining plates between said arms and the axle, said axle containing a grease chamber having a grease outlet communicating with said races, and one of said screws being provided with a grease inlet and a closure therefor.

7. A caster comprising a load-engaging two-armed yoke, an axle interposed between the yoke arms, an annular wheel surrounding the axle and composed of two independently rotatable sections, each having an outer and an inner inwardly facing shoulder race concentric with the periphery of the axle, and an inwardly projecting separating member between said shoulders, rollers interposed between said races and the periphery of the axle, there being two series of rollers for each wheel section, end confining plates interposed between the yoke arms and the ends of the axle and extending across the outer races, securing means engaging the axle with the yoke arms and clamping said end plates between the arms and the ends of the axle, and an intermediate confining plate supported by the axle between the wheel sections and extending across the inner races.

8. A caster comprising a load-engaging two-armed yoke, an axle interposed between the yoke arms, an annular wheel surrounding the axle and composed of two independently rotatable sections, each having an outer and an inner inwardly facing shoulder race concentric with the periphery of the axle, and an inwardly projecting separating member between said shoulders, rollers interposed between said races and the periphery of the axle, there being two series of rollers for each wheel section, end confining plates interposed between the yoke arms and the ends of the axle and extending across the outer races, securing means engaging the axle with the yoke arms and clamping said end plates between the arms and the ends of the axle, and an intermediate confining plate supported by the axle between the wheel sections and extending across the inner races, each wheel section being provided with annular grooves in its outer and inner sides and the said end and intermediate confining plates being provided with dirt-excluding flanges projecting into said grooves.

In testimony whereof I have affixed my signature, in presence of two witnesses.
